UNITED STATES PATENT OFFICE

2,439,656

RECEIVER PROTECTIVE DEVICE

Walter Hausz, Schenectady, N. Y., assignor to
 General Electric Company, a corporation of
 New York

Application August 17, 1942, Serial No. 455,050

7 Claims. (Cl. 250—13)

1

My invention relates to high frequency transmission systems and it has for one of its objects to provide improved means to protect the receiver of such systems from high voltages to which the line, over which the received oscillations are transmitted, may be subjected.

My invention relates more particularly to transmission systems in which both a transmitter and receiver are connected to a common line which may lead, for example, to an antenna by which desired oscillations are radiated and received, and it has for one of its objects to provide an improved means to protect such a receiver from the intense oscillations produced by the associated transmitter.

Another object of my invention is to provide such means particularly adapted for use at short wave lengths.

In such apparatus operating at short wave lengths, and particularly that class of apparatus in which the oscillations produced by the transmitter occur in short pulses which are radiated and then again received after reflection from a remote reflecting surface, one means for protecting the receiver comprises a non-linear impedance device connected across the end of a stub transmission line of such length and so connected to the line as to produce low impedance across it during operation of the transmitter and high impedance during reception of the received echo.

One of the objects of my invention is to effect certain improvements in the operation of such apparatus and in particular to improve the protection afforded the receiver by such apparatus.

Another object of my invention is to provide such an arrangement of the apparatus that certain undesired effects during reception, produced upon the line by the impedance of the transmitter, are avoided.

The features of my invention which I believe to be novel are set forth with particularity in the appended claims. My invention, itself, however, together with further objects and advantages thereof, may best be understood by reference to the following description taken in connection with the accompanying drawing in which Fig. 1 shows diagrammatically the equivalent electrical circuit of my protective device and Fig. 2 shows a physical embodiment of the device.

Referring to the drawing, I have shown in Fig. 1 transmitting apparatus 1 and receiving apparatus 2 connected by means of branch transmission lines 3 and 4 respectively to a main transmission line 5. Transmission line 5, in turn, may

2

be connected to a single directive antenna, not shown. The transmitter 1, at predetermined intervals, supplies a pulse of high intensity over the main transmission line 5 to the antenna, then 5 is inoperative while this signal travels through space to a reflecting object and returns to the system to be picked up by the antenna and detected in the receiving apparatus 2. As will be readily understood the reflected signal is much 10 weaker than that supplied by the transmitting apparatus and the receiving apparatus must be adapted to detect this weaker signal. Since both the transmitting and the receiving apparatus are connected to the transmission line 5, the receiving apparatus may be adversely affected by the strong signal of the transmitter unless means is provided for preventing the transmitted signal from reaching the receiving apparatus over transmission lines 5 and 4 during the transmitting period. Also, during reception, the transmitter 1 and the branch line 3, by causing reflections of the signal at the junction of lines 5 and 3, may adversely affect transmission of the 15 relatively weak returning signal over the line 5 to the receiver unless the transmitter and the connecting line 3 are electrically isolated from the system during the receiving period.

In accordance with my invention the junctions of branch lines 3 and 4 with main line 5 are 20 spaced apart by a distance equal to an odd multiple of an electrical quarter wave length of the radiated oscillations of the pulses produced by the transmitter 1. In using the term "odd" multiple, I mean to include the multiple one. The 25 junction points of branch lines 3 and 4 with main line 5 have been designated respectively as points 6 and 7. Because of the spacing of these junctions, a short circuit across line 5 at point 7, by reason of the impedance inversion effect 30 of the line, well known in transmission-line theory, appears as a very high impedance across the line at point 6.

As one means for short-circuiting transmission line 5 at point 7 during a transmitting period, I 35 provide a stub transmission line 8 connected to the main line 5 at the junction point 7 by means of a short coupling line 9. Stub line 8, comprising an outer conductor 10 and an inner centrally disposed conductor 11, is short-circuited 40 at its lower end at the point 12 and is terminated at its remote end by means of a non-linear impedance device 13. For a purpose to be pointed out later, coupling line 9 is connected to the inner and outer conductors of stub line 8 at a 45 point close to the short-circuiting point 12. De-

vice 13 may be a diode, a spark gap, or any other suitable impedance member having a non-linear impedance characteristic. For purposes of illustration I have shown device 13 as a spark gap, the spacing of the electrodes being such that the gap is non-conducting during the reception of the relatively weak reflected signals picked up by the antenna, but breaks down and becomes conducting whenever the transmitter sends out a pulse of high intensity.

The electrical length of the stub line 8 between the short-circuit point 12 and the terminating gap 13 is made equal to an odd multiple of a quarter wave length of the output wave of the transmitter. For a wave of this frequency, line 8 is a resonant line short-circuited at one end and terminated in a non-linear impedance at the opposite end.

At the low voltages present in the system when the antenna is receiving signals and supplying them over line 5 to the receiving apparatus 2, the tuned line 3 presents a very high impedance to the short coupling line 9 and consequently has very little effect on signals transmitted on line 5. When the transmitter 1 is sending out a signal pulse of high intensity, however, voltages of an intensity sufficient to break down the spark gap 13 are built up on lines 5 and 8, conduction of current between the electrodes of the gap resulting in the detuning of stub line 8. Under this condition, since the coupling line 9 is joined to the stub line 8 at a point close to the short-circuiting connection 12, the stub line presents but a small net inductive reactance across the main line 5. In order to reduce still further the value of the impedance presented across line 5, variable capacitor 14 is connected between the inner conductors of main line 5 and stub line 8 and is adjusted to series-resonate with the small inductive reactance of the stub line. As a result the combination of the stub line, the short coupling line, and the capacitor 14 appears as a substantial short-circuit across main transmission line 5 at the point of its junction with line 4 connecting it to the receiving apparatus. By careful adjustment of the capacitor 14 to the point of exact resonance with the stub line, the value of the resistance presented across the main transmission line at this junction point may be reduced to a value less than one ohm so that the receiving apparatus is effectively short-circuited from the high-intensity signal developed by the transmitting apparatus. Since, as previously stated, the length of the main line between the points of connection with the branch lines 3 and 4 is an odd multiple of a quarter wave length of the output wave of the transmitter, the short circuit across the main line at the point 7 is inverted by the transmission line 5 to appear as the high impedance at the junction point 6. Hence, while the series-resonant circuit comprising stub line 8 and capacitor 14 effectively prevents the transmitter output from reaching the receiving apparatus, this circuit has no effect on the transmitting apparatus itself.

When the gap 13 is non-conductive and the receiving apparatus 2 is adjusted for the reception of signals, it may be found that the branch line 3 and the transmitting apparatus present such an impedance to the main line 5 at the point 6 that reflections occur. If the impedance presented by the branch line 3 to the main line at the point 6 is quite high, the effect of this line on the receiving circuit is negligible; but if the impedance is low, it may cause reflections on the

main line and tend to attenuate the received signal. Variable coupling capacitor 15, in series with the inner conductor of the line 4, and variable coupling capacitor 16 connected across the stub line 8 are provided to compensate for such a low impedance at junction 6 in a manner now to be described.

If there is a low net capacitive susceptance at the junction point 6, capacitor 15 may be adjusted so that the branch line 4 presents a low capacitive reactance plus the receiver resistance to the main line 5 at the point 7. The portion of line 5 which lies between points 6 and 7, being an odd multiple of a quarter wave length of the output wave in length, acts to invert the low capacitive reactance presented by the line 4 in both phase and magnitude, thus giving a low net inductive susceptance in parallel with the conductance of the receiver at the junction point 6. The value of this inductive susceptance may be adjusted by means of capacitor 15 to cancel the capacitive susceptance presented by line 3, leaving only the receiver conductance, previously matched to that of the line 5.

If, on the other hand, there is a low net inductive susceptance presented by line 3 at the junction point 6, capacitor 16 may be adjusted to detune the resonance of stub line 8 so that the net reactance at the junction point 7, including the stub line in parallel with capacitor 15 and the receiver 2, is a low inductive reactance. The portion of line 5 between points 6 and 7 again acts to invert this reactance in both phase and magnitude so that it is effective to produce a low capacitive susceptance at the junction point 6. The value of the capacitive susceptance may be adjusted by means of capacitor 16 to resonate with the low inductive susceptance of transmission line 3, again leaving only the receiver conductance at the point 6.

If as a result of the adjustments outlined in the two preceding paragraphs, the conductance of the receiver, as it appears at the junction point 6, does not match the characteristic conductance of line 5 at this point, further adjustments of both capacitors 15 and 16 may be made to match exactly the impedance of line 2 with that of line 1, thereby completely eliminating reflection.

The system thus described provides a protective device for signalling apparatus, employing both receiving and transmitting equipment connected by means of a single transmission line to an antenna, which both substantially short-circuits the receiving apparatus during the transmitting period and removes the effect of the transmitting apparatus from the receiving apparatus during the receiving period. The resonant line 8 shorted at one end and terminated in a non-linear impedance device at the other end, acts as a parallel resonant circuit presenting a very high impedance across the input when connected to the main transmission line through the coupling capacitor 14. This resonant line has very little effect in the presence of low voltages. When the transmitter is sending out short pulses, voltages sufficient to change the characteristic of the non-linear impedance device occur, thus detuning the resonant line so that it effectively presents only the very small inductive impedance of a short stub on its lower section. By means of the variable capacitor 14, this inductive impedance is series-tuned to present an effective short circuit across the main transmission line. By proper spacing of the junctions of lines 3 and 4 with respect to line 5,

the low impedance which exists across line 4 at junction point 7 is inverted to appear as the high impedance at junction point 6 so that not only is the receiving apparatus protected from intense signals of the transmitter, but also the presence of the receiving apparatus does not affect the operation of the transmitter. Furthermore, by means of variable capacitors 15 and 16, adjusted in the manner previously described, the impedance of line 3 and transmitting apparatus 1 is matched with the impedance of line 5 at the point 6 so that this branch of the system does not cause reflection on the main line 5 during the receiving period.

In Fig. 2 I have shown in greater detail one physical embodiment of the protective system diagrammatically illustrated in Fig. 1. Preferably, the transmission lines 3—5 comprise an outer conducting tube 20 and an inner centrally disposed conductor 21. Suitable insulators 22 are used to retain the conductor 21 centrally disposed with respect to tube 20. The outer tubes and inner conductors of the branch lines may be joined to the outer tube and inner conductor of the main line in any suitable manner, as by soldering, brazing, or the like. The short coupling line 9 may comprise an outer conductor, such as the metal housing 23 soldered or brazed to tubes 10 and 20 of lines 4, 5 and 8 and inner conductors 24 suitably secured to inner conductors 11 and 21 respectively. Connected in series with conductors 24 and located within the member 23, is the multiplate variable capacitor 14 comprising fixed plates 25 and rotatable plates 26. The position of plates 25 with respect to plates 26 may be adjusted in the usual manner by a control knob, not shown.

The inner conductor 11 of the stub line 8 is divided into upper and lower sections, both of which are attached to a metallic cylinder 27, which forms the fixed plate of the variable capacitor 16. The movable plate of capacitor 16 comprises a metal plug member 28 electrically connected, as by means of a flexible cable 29, to the outer tube 10 of stub line 8. The capacitance of capacitor 16, determined by the position of member 28 with respect to member 27, may be adjusted in any suitable manner, such as by means of a rack 30 attached to member 28, pinion 31, and operating handle 32. The plates 27 and 28 are separated by means of an insulating cylinder 33 comprising, preferably, a synthetic material of the polystyrene type having a good power factor.

As previously stated, for purposes of illustration, the non-linear impedance device 13 has been shown as a spark gap and may comprise an electrode 34, having a screw threaded projection 35 from the bottom thereof which may be attached to the end of the inner conductor 11 of the transmission line 8 in a manner to be described later, and an associated electrode 36 which may be mounted upon a conducting plate 37 closing the end of the transmission line 8 and being joined thereto, as by brazing or the like. 65 The space between the electrodes is enclosed by means of a glass cylinder 38 hermetically sealed to the electrode 34 and the conducting plate 37. The electrodes are of solid conducting material and are surrounded within the glass cylinder 38 by a low pressure atmosphere of a gas having a very fast detonization time, such as hydrogen or helium.

In order to provide for ease of assembly of the stub transmission line, as well as to reduce the 75

strain on the glass cylinder 38 during expansion and contraction of the metal of the stub line, conductor 11 is provided with a movable section comprising an inner member 39' attached to the 5 metal cylinder 27 and a sleeve member 39 in threaded engagement with the screw threaded projection 35 and having a plurality of spring-like fingers engaging section 39' of conductor 11 for assuring good electrical contact therewith.

10 Variable capacitor 15 may comprise a fixed plate 40 and a movable plate 41, the fixed plate 40 being connected to conductor 21 in any suitable manner. As shown a screw 42 has one end in threaded engagement with plate 40 and the other end secured to conductor 21, as by brazing or soldering. A disk 43 of suitable insulating material, clamped to plate 40 by means of clamping nut 44, maintains plate 40 centrally disposed with respect to tube 20. Movable plate 41 is 15 preferably joined to a movable conductor 45 having a threaded portion 46 and an adjusting knob 47. A tubular conducting member 48, suitably connected to the portion of conductor 21 extending to the receiving apparatus and supported in spaced relation with tube 20 of line 4 by means of insulating disk 49, surrounds conductor 45 and has a slotted portion comprising a plurality of fingers 50 of spring-like material for making good electrical contact with conductor 45. 20 A nut 51, engaging threads on the outer surface of member 48, is used in conjunction with a retaining ring 52 suitably attached to member 48 to clamp the member 48 to the insulating disk 49, thus fixing the position of member 49 with respect to tube 20. The spacing disk 53 secured 25 within member 48 is internally threaded for engagement with threaded portion 46 of conductor 45. By means of knob 47 and threads 46 and 53, the spacing of variable plate 41 with respect to fixed plate 40 may be adjusted to vary the capacity of condenser 15 for the purposes previously explained.

30 While I have shown a particular embodiment of my invention, it will of course be understood that I do not wish to be limited thereto since various modifications may be made, and I contemplate by the appended claims to cover any such modifications as fall within the true spirit and scope of my invention.

35 What I claim as new and desire to secure by Letters Patent of the United States is:

1. In combination, a transmission line, apparatus connected thereto and operating with respect to oscillations transmitted over said line 45 said line being subjected to high voltages of a certain frequency, means to protect said apparatus from said high voltages, said means comprising a stub line having a length equal to a quarter of a wave length, or odd multiple thereof, of oscillations having the frequency of said high voltages, said stub line being short-circuited at one end and having points spaced from said short circuit connected to opposite sides of said transmission line through a capacitance, and an impedance across the opposite end of said stub line having high value to low voltages and low value to said high voltages, said capacitance having such a value as to resonate with the inductance presented by said stub line when said impedance is low, whereby said stub line and capacitance produce a short circuit across said transmission line during high voltages thereon and high impedance across said line in the absence of said high voltages.

2. In combination, a transmission line, appa-

apparatus connected thereto and operating with respect to oscillations transmitted over said line, said line being subjected to high voltages of a certain frequency, means to protect said apparatus from said high voltages, said means comprising a stub line having a length equal to a quarter of a wave length, or odd multiple thereof, of oscillations having the frequency of said high voltages, said stub line being short-circuited at one end and having an impedance connected across the opposite end thereof having high impedance to low voltage and low impedance to high voltage, and means to supply the high voltage of said transmission line to said impedance and to couple the impedance of said stub line across said transmission line, said means including means to produce series resonance with said impedance of said stub line when said impedance is low thereby to short circuit said transmission line during periods of said high voltages.

3. In radio equipment having transmitting and receiving apparatus and an antenna system, the combination of a transmission line over which oscillations are transmitted between said transmitting apparatus and said antenna, and between said antenna and said receiving apparatus, the points of connection of said apparatuses with said line being spaced apart by a distance equal to an odd multiple of a quarter wave length of said oscillations, means for interrupting transmission of said oscillations to said receiving apparatus when said transmitting apparatus is operating to produce oscillations of high intensity, said means comprising a stub transmission line, a non-linear impedance element connected across one end of said stub line, said element having a low impedance value to said oscillations of high intensity and a high value to oscillations received from said antenna, and reactance means connected between said stub line and said first line at the point of connection with said receiving apparatus for tuning said stub line to series resonance at the frequency of said oscillations when said transmitting apparatus is operating, said stub line and said reactance means being effective when resonating to produce a low impedance across said first line at said point of connection.

4. In combination, a transmission line, receiving apparatus connected thereto to receive oscillations over said line, a transmitter connected to said line to supply oscillations thereover, and an impedance means connected across said line at a point between said transmitter and receiver, the impedance of said means being low during the high voltages produced by said transmitter and high during the absence of said high voltages, said transmitter presenting reactive impedance to said line producing undesired reflections during reception, said impedance means during reception presenting like reactance to said line at said point, the distance between said point and the point of connection of said transmitter being such that said reactances appear in opposite sense at the point of connection of said transmitter, and the impedance of said impedance means being of such value that resonance occurs at said point of connection of said transmitter.

5. In combination, a transmission line, receiving apparatus connected thereto to receive oscillations over said line, a transmitter connected to said line to supply oscillations thereover, said

transmitter presenting reactive impedance to said line producing undesirable reflections during reception, impedance means connected between said apparatus and said line, said impedance means during reception presenting like reactance to said line, the distance between said impedance means and the point of connection of said transmitter being such that said reactances appear in opposite sense at the point of connection of said transmitter, and the impedance of said impedance means being of such value that resonance occurs at said point of connection of said transmitter.

6. In combination, a receiver, a transmission line extending thereto over which oscillations are received, a transmitter connected thereto at a point distant from said receiver presenting undesired reactance to said line, and means to protect said receiver from voltages produced by said transmitter and to avoid reflections produced by said reactance, said means comprising a stub line connected across said transmission line at a point between said transmitter and receiver and presenting high impedance thereto between periods of operation of said transmitter, means to reduce said impedance to a low inductive value in response to oscillations produced by said transmitter, means connected to said stub line to resonate with said low inductive impedance at said point and to render said high impedance reactive and of like sign to the impedance of said transmitter, said point being so spaced from the connection between said transmission line and transmitter that said transmitter reactance and said high impedance appear of unlike signs at the point of connection of said transmitter.

7. In combination, a receiver, a transmission line extending thereto over which oscillations are received, a transmitter connected thereto at a point distant from said receiver presenting undesired reactance to said line, and means to protect said receiver from voltages produced by said transmitter and to avoid reflections produced by said reactance, said means comprising a stub line connected across said transmission line at a point between said transmitter and receiver and presenting high impedance thereto between periods of operation of said transmitter, means to reduce said impedance to a low inductive value in response to oscillations produced by said transmitter, means connected to said stub line to resonate with said low inductive impedance at said point, and reactance means connected between said receiver and said point, said reactance means being effective to provide a reactance at said point of like sign to said undesired reactance, said point being so spaced from the connection between said transmission line and said transmitter that resonance occurs between said reactance and said undesired reactance at said connection of said transmitter.
